ELECTROLUMINESCENT SCREEN AND DEVICE
David W. Morgan, East Orange, N.J., assignor to Westinghouse Electric Corporation, East Pittsburgh, Pa., a corporation of Pennsylvania

Filed Dec. 7, 1959, Ser. No. 857,897
7 Claims. (Cl. 315—169)

This invention relates to electroluminescent display screens and devices and, more particularly, to an electroluminescent display screen for visually presenting signal information and an electroluminescent device which incorporates such a display screen.

The phenomenon of electroluminescence was first disclosed by G. Destriau, one of his earlier publications appearing in London, Edinburg and Dublin Philosophical Magazine, Series 7, volume 38, No. 285, pages 700-737 (October 1947). Since this time, electroluminescent devices have been marketed commercially and considerable developments have been made with respect to application devices which utilize electroluminescence. A fairly recent summary of electroluminescence and related subjects can be found in Destriau and Ivey article in "Proceedings of the I.R.E.", volume 43, No. 12, pages 1911-1940 (December 1955).

Present oscilloscopes rely on a cathode-ray tube for visual presentation of signal information. The tube is cumbersome and the oscilloscope must be made correspondingly large. In addition, the signal information is necessarily presented as a trace on the screen of the cathode-ray tube. For some applications, it is desirable to have signal information presented in an integrated fashion so that all of the area below the trace is illuminated. Such a presentation is not practical with present cathode-ray tubes.

It is the general object of this invention to provide an electroluminescent display screen for presenting signal information in an integrated fashion so that all of the area below the top portion of the presented signal is illuminated.

It is a further object to provide an electroluminescent oscilloscope wherein the cathode-ray tube is replaced by a compact electroluminescent display screen.

It is an additional object to provide an electroluminescent oscilloscope wherein the electroluminescent display screen presents information in such fashion that all area below the top portion of the presented signal is illuminated.

The aforesaid objects of the invention, and other objects which will become apparent as the description proceeds, are achieved by providing an electroluminescent display screen which comprises a plurality of closely-spaced and side-by-side electroluminescent cells. Each of the cells has a varying physical spacing between the electrodes so that a cell cross section has a generally wedge-shaped configuration. Each of the cells which comprise the screen are a part of a different tuned circuit, each having a different resonant frequency. Such a display screen can be used as a part of an electroluminescent oscilloscope wherein an alternating potential periodically varying over a range of frequencies is applied to the tuned circuits and cell electrodes of the display screen. The period of frequency variation is synchronized with the period of the signal to be presented and the varying frequency potential is amplitude modulated with this signal. When the resulting varying frequency, modulated potential is applied across the tuned circuits and electroluminescent cells comprising the screen, the individual tuned circuits will resonate in sequence. As each tuned circuit resonates, the cell which forms a part of such tuned circuit electroluminesces in amount varying with the voltage which is applied across the cell electrodes.

2

The persistence of the observer's eye blends together the resulting individual light signals so that all area below the top or upper portion of the presented signal is illuminated.

5 For a better understanding of the invention, reference should be had to the accompanying drawings wherein:

FIG. 1 is a perspective view, partly broken away, showing an electroluminescent display screen fabricated in accordance with the present invention;

FIG. 2 is a cross-sectional side elevation of an alternative construction for a screen generally as shown in FIG. 1;

10 FIG. 3 is a cross-sectional side elevation of another alternative construction for a screen generally as shown in FIG. 1;

15 FIG. 4 is a diagrammatic sketch showing an electroluminescent signal display device which functions as an oscilloscope.

With specific reference to the form of the invention 20 illustrated in the drawings, the electroluminescent screen 10 as shown in FIG. 1 generally comprises a glass foundation 12 having coated thereover a light-transmitting, tin oxide electrode layer 14. Coated over the tin oxide layer 14 is a phosphor-dielectric layer 16. Carried over 25 the phosphor-dielectric layer 16 is a wedge-shaped layer 18 of polyethylene terephthalate. Over the wedge-shaped dielectric layer 18 are carried a series of closely-spaced aluminum electrode strips 20 positioned in side-by-side relationship, with each of the electrodes 20 having a 30 length dimension of considerable magnitude and a width dimension of small magnitude. Each of these electrode segments 20 is insulated from the adjacent electrode segment and this in effect forms a plurality of side-by-side electroluminescent cells 22, even though the light-transmitting electrode 14 is common to all cells.

35 There is also provided a plurality of different tuned circuits, one of each of which incorporates as a circuit element a different one of the cells 22 comprising the screen 10. In the example as shown, each tuned circuit 40 is formed as a series-connected inductor 24, 24a, etc. and capacitor 26, 26a, etc. connecting across the screen input terminals. Each tuned circuit thus essentially comprises 45 an inductor having two parallel-connected capacitors connecting in series therewith, one of which capacitors is a cell 22. The individual values of inductance and capacitance are so chosen that each tuned circuit displays a different resonant frequency and the resonant frequencies vary from a minimum for the tuned circuit including the cell 22 positioned at one edge of the screen 10 to a maximum for the tuned circuit including the cell 22 positioned at the opposite edge of the screen 10.

50 As a specific example, the screen 10 as illustrated in FIG. 1 is formed of twenty-five individual electroluminescent cells. The electrode strip 20, which define the dimensions of each of the cells 22 which comprise the screen 10, each have a length of 5 centimeters and a width of 2 millimeters with a spacing of 2 mils therebetween. The phosphor-dielectric layer 16 has a thickness of 2 mils and the wedge-shaped plastic layer 18 has a thickness of 1 mil at the thinnest end and 4 mils at the thickest end. The display screen 10 thus has overall dimensions of approximately 5 cms. by 5 cms. As a specific example, the average capacitance for each of the cells 22 is approximately 100 micromicrofarads and the individual tuned circuits which include the individual cells 22 as a component are designed to resonate at frequencies varying from 940 c.p.s. to 1,060 c.p.s., with a resonant frequency differential of 5 c.p.s. between each adjacent cell 22. The circuit components required to cause resonance under such conditions of operation are readily calculated. As 55 an example, the tuned circuit incorporating the individual cell 22 which is positioned at the left-hand edge of the

screen 10, as viewed in FIG. 1, is intended to resonate at a frequency of 940 c.p.s. For this condition of resonance, the inductance of this tuned circuit can have a value of 1×10^{-2} henry and the added capacitance of this tuned circuit can have a value of 6.25 microfarads. The tuned circuit incorporating the individual cell 22 which is positioned at the right-hand edge of the screen 10 as viewed in FIG. 1, resonates at a frequency of 1060 c.p.s. In order to produce this desired resonant frequency, the inductance 24 of this tuned circuit can have a value of 1×10^{-3} henry and the added capacitance 26 of this tuned circuit can have a value of 2.5 microfarads. The other inductances and added capacitances required to cause each tuned circuit to resonate as indicated are readily calculated.

Any suitable electroluminescent phosphor can be used in forming the layer 16. As a specific example, a green-emitting electroluminescent phosphor is prepared by mixing 1,000 grams zinc sulfide with 30 grams sulphur, 12.8 grams copper acetate and 4.5 grams ammonium chloride. This mixture is fired in a partially-closed container in a nitrogen atmosphere at a temperature of about 950° C. for about 100 minutes. Thereafter the phosphor is slightly crushed, 3 grams of sulphur are added to the phosphor and it is refired in a similar manner. After final firing, the phosphor is lightly crushed and is washed with a solution which is a solvent for cuprous sulfide, but which is not a solvent for zinc sulfide. An example of such a washing solution is sodium cyanide. Any other electroluminescent phosphor can be substituted for the foregoing example and reference is made to the aforementioned Destriau and Ivey publication for a listing of other electroluminescent phosphors. For best delineation of the presented signal, it is preferred to use a so-called steep-slope electroluminescent phosphor and such phosphors are well known.

The foregoing specific screen is subject to considerable variation. In the preferred example, the light-transmitting electrode 14 is formed as one continuous electrode, common to all cells 22. If desired, the light-transmitting electrode can be scribed so as to form a plurality of small electrodes, each having a configuration which conforms with that of the opposing electrode strip 20. While tin oxide is preferred for the light-transmitting electrode 14, this electrode can be formed as a series of parallel wires or alternatively, other light-transmitting electrically-conducting materials such as indium oxide can be substituted for the tin oxide. The phosphor-dielectric layer 16 is subject to variation with respect to thickness and with respect to composition. As an example, equal parts by weight of the foregoing specific electroluminescent phosphor and a light-transmitting dielectric material such as polyvinyl-chloride acetate can be mixed and used as the layer 16. Other suitable plastic or ceramic dielectric materials can be substituted for this specific example. The thickness of the phosphor-dielectric layer 16 can be varied considerably and the relative proportions of phosphor and dielectric are also subject to variation. Different plastic and ceramic dielectric materials can also be used in forming the wedge-shaped layer 18. The electrode strips 20, while desirably fabricated of vacuum-metallized aluminum, can also be fabricated of any suitable conducting material conformed as indicated and light-transmitting electrode material such as copper iodide can be substituted for the vacuum-metallized aluminum. The actual configuration of the electrode strips 20 is subject to considerable variation and more or fewer strips can be used as desired. Variation of the foregoing example with respect to dimensions, etc. will require that the elements of the tuned circuits be modified in order to cause the tuned circuits incorporating the individual cells to resonate at the desired frequencies and the required values for these elements can be readily calculated. Likewise, the frequency differential between adjacent cells and the overall frequency range used can be varied or shifted if desired.

In FIG. 2 is shown an alternative screen embodiment 10a which generally comprises a light-transmitting foundation 12a having a light-transmitting electrically-conducting layer 14a thereover. The phosphor-dielectric layer 16a has a varying thickness, gradually increasing from a minimum thickness at the bottom of the screen to a maximum at the top. The surface of the phosphor-dielectric layer 16a furthest removed from the light-transmitting foundation 12a has a stepped configuration with the dimensions of the risers of the steps 23 determining the thickness variation between electrodes. The outermost electrodes 20a are vacuum metallized over the steps 23. Such a construction results in more contrast in the delineation of the top portion of any signal which is to be presented and resolution for the top portion of any presented signal is determined by the width of each of the individual steps 23.

In FIG. 3 is shown another alternative screen construction 10b wherein the glass foundation 12b and light-transmitting coating 14b are as previously illustrated. The phosphor-dielectric layer 16b has a thickness which gradually increases as a greater-than-linear rate. The uneven rate at which the thickness increases will produce a sharper cut-off for the top portion of any signal which is to be presented. Other than this, the screen embodiment 10b generally corresponds to the other screen embodiments shown.

In FIG. 4 is shown in diagrammatic form an electroluminescent signal display device 30 which functions similarly to an oscilloscope, but wherein the usual cathode-ray tube is replaced by a compact electroluminescent display screen 10. Briefly, the device 30 comprises a conventional Hartley oscillator 32 which is variable with respect to frequency. The oscillator capacitor 34 is variable and is driven by a motor 36 adapted to be manually controlled with respect to speed. The capacitor 34 is preferably formed of two individual sections which operate 180° out of phase so that while one section is at full capacity, the other section is at least capacity. As the variable capacitor 34 is rotated, the oscillator output periodically sweeps the predetermined frequency range established by the extremes of the resonant frequencies of the tuned circuits of which the cells 22 comprising the screen 10 form a part.

The varying frequency output potential of the oscillator 32 is fed into the grid of a conventional modulating tube 38 and the signal to be presented is impressed across the primary of transformer 40 to modulate the plate voltage of the tube 38. An additional tuned circuit 42 isolates the transformer 40 from the output of the tube 38. Such a circuit arrangement is conventional. The resulting modulated varying frequency potential output of the tube 38 is fed into a standard amplifier 44, shown in block diagram. The output of the amplifier 44 is connected across the input terminals of the screen 10. As the frequency is varied over the predetermined range, each of the tuned circuits which include the individual electroluminescent cells 22 will resonate in turn, resulting in applying a large potential across the cell components of the tuned circuits during resonance. The maximum applied potential varies with the amplitude modulation of the output of the amplifier 44 and because of the varying thickness between electrodes of the cells 22, the individual cell which forms a part of a resonating circuit electroluminesces in brightness and area in an amount which corresponds to the applied voltage. In other words, a larger voltage will cause a greater portion of the cell to emit visible light during resonance. This produces in visual fashion on the electroluminescent screen 10 a signal presentation which corresponds to the signal input to the modulating tube 38. It is necessary to synchronize the speed of the motor 36 with the period of the signal which is to be presented so that the speed of the motor 36 is either a whole multiple or a whole fraction of the period of the signal

which is to be presented. This is readily accomplished by means of the manual speed control 46, which can be adjusted accordingly. As an example, if the period of the signal to be presented is $\frac{1}{40}$ sec., the capacitor 34 is rotated at 40 r.p.s. The varying frequency output potential of the oscillator 32, the input signal to be presented, the amplitude-modulated varying-frequency output of the amplifier 40 and the resulting signal presentation on the screen 10 are all shown as diagrammatic signal representation in FIG. 4.

Some of the circuit components comprising the foregoing electroluminescent oscilloscope 30 can be replaced by other conventional components which function in a similar manner. As an example, the potential generating means, which is preferably a Hartley oscillator, can be replaced by other conventional oscillators. The manually controlled motor 36, which essentially functions as a synchronizing means to synchronize the periodic variations in frequency of potential generated by the oscillator 32 with the period of the signal to be presented, can be replaced by conventional electronic synchronizing means. The modulating tube 38 can be replaced by other conventional modulating means, in order to modulate the synchronized varying-frequency potential with amplitude modulation corresponding to the signal to be displayed.

The present screen can also be used in applications other than an oscilloscope. As an example, the individual electroluminescent cells 22 which comprise the screen 10 as shown in FIG. 1 can be calibrated with respect to voltage and with respect to the resonant frequency of the tuned circuits of which the cells 22 form a part. In this manner, a direct simultaneous reading of frequency and potential can be obtained when a potential of unknown voltage and unknown frequency is applied across the screen input terminals.

It will be recognized that the objects of the invention have been achieved by providing an electroluminescent display screen for presenting signal information in an integrated fashion so that all of the area below the top portion of the presented signal is illuminated. There has also been provided an electro-luminescent oscilloscope wherein the cathode-ray tube is replaced by a compact electroluminescent display screen and wherein all the area below the top portion of any signal presented is illuminated.

While best specific examples of the invention have been illustrated and described hereinbefore, it is to be particularly understood that the invention is not limited thereto or hereby.

I claim:

1. A display screen comprising: a plurality of closely-spaced and side-by-side electroluminescent cells; each closely-spaced cell of said screen comprising, two spaced electrodes at least one of which is light transmitting and each having a length dimension of considerable magnitude and a width dimension of small magnitude, the physical spacing between said electrodes gradually varying from a minimum proximate one end of said cell to a maximum proximate the other end of said cell, and material comprising electroluminescent phosphor included between said spaced electrodes; like ends of each of the closely-spaced cells comprising said screen positioned in side-by-side relationship; a plurality of tuned circuits each incorporating as a component thereof a different one of the cells comprising said screen; and each said tuned circuit displaying a different resonant frequency varying from a minimum for the circuit incorporating the cell positioned at one edge of said screen to a maximum for the circuit incorporating the cell positioned at the opposite edge of said screen.

2. A display screen comprising: a plurality of closely-spaced and side-by-side electroluminescent cells; each closely-spaced cell of said screen comprising, two spaced electrodes at least one of which is light transmitting and each having a length dimension of considerable magni-

tude and a width dimension of small magnitude, the physical spacing between said electrodes stepped in gradual fashion from a minimum proximate one end of said cell to a maximum proximate the other end of said cell, and material comprising electroluminescent phosphor included between said spaced electrodes; like ends of each of the closely-spaced cells comprising said screen positioned in side-by-side relationship; a plurality of tuned circuits each incorporating as a component thereof a different one of the cells comprising said screen; and each said tuned circuit displaying a different resonant frequency varying from a minimum for the circuit incorporating the cell positioned at one edge of said screen to a maximum for the circuit incorporating the cell positioned at the opposite edge of said screen.

3. A display screen comprising: a plurality of closely-spaced and side-by-side electroluminescent cells; each closely-spaced cell of said screen comprising, two spaced electrodes at least one of which is light transmitting and each having a length dimension of considerable magnitude and a width dimension of small magnitude, the physical spacing between said electrodes gradually varying from a minimum proximate one end of said cell to a maximum proximate the other end of said cell, and a mixture of electroluminescent phosphor and light-transmitting dielectric material sandwiched between said spaced electrodes; like ends of each of the closely-spaced cells comprising said screen positioned in side-by-side relationship; a plurality of tuned circuits each incorporating as a component thereof a different one of the cells comprising said screen; and each said tuned circuit displaying a different resonant frequency varying from a minimum for the circuit incorporating the cell positioned at one edge of said screen to a maximum for the circuit incorporating the cell positioned at the opposite edge of said screen.

4. A display screen comprising: a plurality of closely-spaced and side-by-side electroluminescent cells; each closely-spaced cell of said screen comprising, two spaced electrodes at least one of which is light transmitting and each having a length dimension of considerable magnitude and a width dimension of small magnitude, the physical spacing between said electrodes gradually varying from a minimum proximate one end of said cell to a maximum proximate the other end of said cell, a layer of even thickness comprising electroluminescent phosphor included between said spaced electrodes, and an additional layer of dielectric material of gradually increasing thickness also included between said electrodes; like ends of each of the closely-spaced cells comprising said screen positioned in side-by-side relationship; a plurality of tuned circuits each incorporating as a component thereof a different one of the cells comprising said screen; and each said tuned circuit displaying a different resonant frequency varying from a minimum for the circuit incorporating the cell positioned at one edge of said screen to a maximum for the circuit incorporating the cell positioned at the opposite edge of said screen.

5. A display screen comprising: a plurality of closely-spaced and side-by-side electroluminescent cells; each of the closely-spaced cells of said screen comprising, two spaced electrodes at least one of which is light transmitting and each having a length dimension of considerable magnitude and a width dimension of small magnitude, a cross section taken between said electrodes having a generally wedge-shaped configuration, and material comprising electroluminescent phosphor included between said spaced electrodes; like ends of each of said closely-spaced cells positioned in side-by-side relationship in said screen; a different tuned circuit connecting to each of the cells comprising said screen; and each said tuned circuit and connecting cell displaying a different resonant frequency varying from a minimum for the circuit and connecting cell positioned at one edge of said screen to a maximum

for the circuit and connecting cell positioned at the opposite edge of said screen.

6. A display screen comprising: a plurality of closely-spaced and side-by-side electroluminescent cells; each closely-spaced cell of said screen comprising, two spaced electrodes at least one of which is light transmitting and each having a length dimension of considerable magnitude and a width dimension of small magnitude, the physical spacing between said electrodes gradually increasing at a greater-than-linear rate from a maximum proximate one end of said cell to a maximum proximate the other end of said cell, and material comprising electroluminescent phosphor included between said spaced electrodes; like ends of each of the closely-spaced cells comprising screen positioned in side-by-side relationship; a plurality of tuned circuits each incorporating as a component thereof a different one of the cells comprising said screen; and each said tuned circuit displaying a different resonant frequency varying from a minimum for the circuit incorporating the cell positioned at one edge of said screen to a maximum for the circuit incorporating the cell positioned at the opposite edge of said screen.

7. A signal display device comprising: a signal-presentation screen comprising a plurality of closely-spaced and side-by-side electroluminescent cells; each closely-spaced cell of said screen comprising, two spaced electrodes at least one of which is light transmitting and each having a length dimension of considerable magnitude and a width dimension of small magnitude, the physical spacing between said electrodes gradually varying from a minimum proximate one end of said cell to a maximum proximate the other end of said cell, and material comprising electro-

luminescent phosphor included between said spaced electrodes; like ends of each of the closely-spaced cells comprising said screen positioned in side-by-side relationship; a plurality of tuned circuits each incorporating as a component thereof a different one of the cells comprising said screen; each said tuned circuit displaying a different resonant frequency varying from a minimum for the circuit incorporating the cell positioned at one edge of said screen to a maximum for the circuit incorporating the cell positioned at the opposite edge of said screen; potential-generating means for generating alternating potential periodically varying in frequency throughout the range established by the resonant frequencies of said tuned circuits; synchronizing means for synchronizing the periodic variations in frequency of potential generated by said potential-generating means with the period of the signal to be presented; modulating means for modulating the synchronized varying-frequency potential generated by said potential-generating means with amplitude modulation corresponding to the signal to be displayed; and means for applying across said tuned circuits the synchronized modulated varying frequency output of said modulating means; whereby the signal to be displayed is presented in visual form on said presentation screen.
